J. F. KELLY.
LOCKING DEVICE FOR ELECTRICALLY OPERATED PIANOS.
APPLICATION FILED MAY 31, 1912.

UNITED STATES PATENT OFFICE.

JOHN F. KELLY, OF PITTSFIELD, MASSACHUSETTS.

LOCKING DEVICE FOR ELECTRICALLY-OPERATED PIANOS.

1,112,143.

Specification of Letters Patent. Patented Sept. 29, 1914.

Application filed May 31, 1912. Serial No. 700,761.

To all whom it may concern:

Be it known that I, JOHN F. KELLY, a citizen of the United States of America, residing at Pittsfield, in the county of Berkshire and State of Massachusetts, have invented new and useful Improvements in Locking Devices for Electrically-Operated Pianos, of which the following is a specification.

This invention relates to improvements in electrically operated piano players and in particular relates to the subject matter shown, described and claimed in my prior United States application for Letters Patent No. 1,651,314 filed September 26, 1911 in which application the actions of the piano are operated by means of a bank of electro-magnets located immediately back of the fall-board of the instrument, so that when any one of the magnets of the bank is energized by means of the electric circuit being closed through a suitable perforation in the note-sheet the individual action would be operated similar to the manner in which the instrument is manually operated. In this above-referred-to application no means was shown or provided for retaining the keys of the instrument in an elevated position when the action was electrically operated, or in other words, the keys would drop at their forward ends when the weight of the actions were removed from the rear portions of the keys. The present invention is designed to overcome this objection and is so constructed and arranged that when the note-sheet is drawn through the circuit closing device a suitable opening in the note-sheet will cause the closure of the circuit to a suitable electro-magnet, which in turn, will cause the locking bar to be moved into contact with the rear portions of the keys. When this bar is in its locking position the keys will be retained in their normal elevated or horizontal positions, and cannot be manually operated, nor can they fall or drop when the weight of the action is removed from their inner ends. In general this locking device comprises a bar member in which its longest axis stands in a vertical plane or position when the bar is serving to lock the keys, and its longer axis will lie in a horizontal plane when the keys are unlocked. It is to be understood, however, that I do not limit myself to the precise construction of this locking bar as the above-

mentioned form is merely illustrative of its function and operation of this member.

Referring to the drawings:—Figure 1 is a sectional view through the key-board of a piano of the upright type illustrating one unit of the action and one of the operating magnets of the bank that moves the action; the locking bar being shown in a position to retain the keys against movement. Fig. 2 is a detailed view of the electro-mechanical means for operating the locking bar and the magnet for releasing or unlatching this bar at the termination of the playing of a piece of music.

Referring to the drawings in detail *a* designates the usual key-bed of the instrument, *b* one of the keys, *c* one form of fall-board, which is adapted to be moved forward and backward on the track *d*. One of the units of the action of the instrument is designated *e* as a whole by the letter *e*, and one of the piano wires is shown at *e*¹ against which the hammer *e*² strikes. One of the magnets of the bank is designated by the letter *f*, which bank is carried by the bar *g* that extends lengthwise of the instrument and is suitably secured to the casing or frame work at its opposite ends.

h designates an electro-magnet of the same type as the magnets composing the bank, one of which is shown at *f*. These magnets, preferably two in number, are located at the opposite ends of the instrument.

i designates the armature of this magnet, which is the same in construction as that shown in the patent to Powers and Jewell No. 753,809, March 1, 1904 (see Fig. 20), and attached or secured to this armature is the locking bar *j* that extends lengthwise of the instrument which is located immediately above the inner ends of the keys *b*. This bar is provided with an arm *k* attached thereto to which is connected a spring *m*, its opposite end being suitably secured to a fixed support as shown at *o*. An arm *p* is attached to the bar *j* and extends outward into the path of the lower end of the lever *q* which is pivotally mounted to the casing as shown at *r* and is normally drawn toward the left by means of the spring *s*. The outer end of the arm *p* is notched, as shown, to prevent the lever *q* being drawn too far inward by the spring *s*.

t designates an electro-magnet that is arranged to attract the lever *q* when energized

and effect the release of the arm *p*. This electro-magnet is energized after the current is closed to the bank of magnets *f* by means of a suitable slot in the note-sheet 5 permitting the current to flow to this magnet causing the lever *q* to be attracted thereby unlocking the arm *p* and permitting the spring to turn the bar *j* into a horizontal plane position. When the bar *j* is in the 10 locking position shown in Fig. 1 it is clear that the keys *b* cannot fall when the weight of the action *e* is removed from the inner end of the keys and also the keys cannot be manually operated while the instrument is 15 being electrically operated.

In operation the bar *j* is moved by the armature *i* of the electro-magnet *h* to its locking position, shown in Fig. 2, by means of a suitably placed slot in the note-sheet 20 which closes an electrical-connection to the magnet *h* and causes the armature *i* and the bar *j*, to which it is attached, to be turned to the vertical position shown. This slot should be located at the commencement of 25 the playing of the piece, thus effecting a saving in the consumption of electric energy. By locating the slot which effects the closure of the electric circuit to the magnet *h* near the commencement of the play- 30 ing of the piece, the necessity of energizing this magnet for any considerable length of time is obviated. The bar will remain in the locking position shown in Fig. 2 until it is released by the magnet *t* 35 attracting the arm *q*, which, releasing operation is effected by means of a suitably located slot in the music sheet at the termination of the piece which will cause the closing of the circuit to the magnet. The 40 lever *q* will then release the arm *p*, whereby the spring *m* will turn the locking bar *j* to the unlocking position.

What I claim, is:

1. A key-locking device for electrically 45 operated pianos comprising a movable member, an electro-magnet to move said member into engagement with the keys to lock the same, means to lock the member when in its key-locking position, a second 50 electro-magnet, and connections operable therefrom to unlock the member and permit the member to move into an unlocking position to release the keys, and means to move said member after it is unlocked.

55 2. In a piano-key locking device, the combination, a rotatably mounted bar located

to engage the rear portion of the keys to lock the same, an electro-magnet to move the bar to a locking position, an electro-magnet to release said bar, an armature for each of said magnets, the bar being secured to the armature of one of the electro-magnets, an arm on the bar, the armature of the other electro-magnet arranged to engage the arm and retain the bar in a position to lock 60 the keys, and means to rotate the bar to a position to unlock the keys when the arm is released whereby when one of the electro-magnets is energized the bar will be moved to an unlocking position and when the other 65 electro-magnet is energized the bar will be moved to a locking position, as described.

3. An electro-mechanical device to lock the manually-operable keys of a piano, electro-magnetic means to operate the tone 75 sounding devices of the instrument, said device comprising, in combination, a rotatably mounted bar located over and adjacent the inner ends of said keys, electro-magnets, armatures therefor, said bar-member being 80 secured to the armature of one of the electro-magnets, means to lock the bar in its locking position, the armature of the other electro-magnet serving to unlock said bar, means to energize said magnets, whereby 85 when one of the magnets is energized the bar is moved to engage the upper surface of the keys to prevent their manual operation, and said keys will be prevented from falling at their forward ends when the instrument is being electrically operated and whereby when the other magnet is energized the bar will be unlocked, as described.

4. In a musical instrument, the combination with the manually-operable keys there- 95 of, electrically operated devices to operate the instrument independently of the manually operable keys, a rotatably mounted member to lock said keys against manual operation, an electro-magnet to operate said 100 member, a second electro-magnet and means operated by the second electro-magnet to release said member, and means to rotate said member after its release by the second electro-magnet to move the same to a position to permit the manual operation of the 105 keys.

JOHN F. KELLY.
